UNITED STATES PATENT OFFICE

143,097

DESIGN FOR A BREATHING APPARATUS

John H. Schneider, Irwin, Pa., assignor to Mine Safety Appliances Company, Pittsburgh, Pa.

Application January 16, 1942, Serial No. 105,238

Term of patent 14 years

(Cl. D83—1)

To all whom it may concern:

Be it known that I, John H. Schneider, citizen of the United States, residing at Irwin, in the county of Westmoreland and State of Pennsylvania, have invented a new, original, and ornamental Design for Breathing Apparatus, of which the following is a specification, reference being had to the accompanying drawings forming a part thereof.

Fig. 1 is a side elevational view of a breathing apparatus embodying my new design;

Fig. 2 is a front elevational view thereof;

Fig. 3 is a bottom plan view of the canister shown in Figs. 1 and 2;

Fig. 4 is a fragmentary top plan view of said canister and its attaching belts.

Fig. 5 is a fragmentary rear elevational view of the canister and connections thereto;

Fig. 6 is another side elevational view of the apparatus.

The dominant features of my design for breathing apparatus are represented in full lines.

I claim:

The ornamental design for a breathing apparatus, substantially as shown and described.

JOHN H. SCHNEIDER.
